FEEDER TRACK AND CLEARING WHEEL
James W. Batchelder, Springfield, Vt., assignor to Textron
Inc., a corporation of Rhode Island
Filed July 11, 1960, Ser. No. 31,963
5 Claims. (Cl. 193—43)

The present invention relates generally to the art of feeding parts or articles; and more in particular to track feeding mechanisms; and specifically to improvements in the combination of a feed track and rejection wheel ensuring the feeding of bolts or other headed objects to a discharge point in a proper orientation serially in soldiered array suspended by their heads on the track.

A great variety of feeding machines and devices are known to the prior art wherein headed objects or parts such as bolts, rivets, or parts of analogous form are delivered along a track suspended by their heads to a discharge point for successive discharge in like disposition as the feed to other machines for further operations, or for counting, packaging or the like. Well known to the prior art is the provision adjacent the track of a circumferentially grooved and toothed or notched rotating rejecting or clearing wheel which clears from the track and rejects improperly positioned parts. Usually such a wheel is positioned to rotate in the vertical plane including the path of travel of the parts immediately adjacent thereto; and the cross section of the circumferential wheel edge groove is of such shape as to permit the heads of properly suspended pieces to pass thereunder, while a spaced circumferential series of edge notches provide teeth with impact faces to kick malpositioned parts from the track.

To further more effective wheel action, it has already been proposed that in the neighborhood of the wheel the track have a downward bend, so that malpositioned parts, particularly those moving along the track with axes disposed in the track plane or substantially so disposed, in passing over the bend or point of track inflection, are thereby exposed to more effective contact action by the wheel.

The present invention addresses itself particularly to track structure adapted to handle headed parts which readily assume and maintain a suspended orientation, but also those of relatively short shank length which by virtue of the relatively large head mass are more likely to move along the feed track without being suspended with shank dependent within the track structure, even though the axes thereof may be actually in the plane of the track. Where, for example, socket head cap screws are being fed, the circumferential groove has a rectangular shape to correspond with the elevational outline of the socket head and is relatively deep over its entire width. In consequence, short shank pieces of this character moving along the track improperly supported on the cylindrical head surface rather than underneath the head may pass under the wheel without rejection. Where such parts are being fed to a counting and packaging machine, an improperly positioned piece escaping under the wheel by virtue of its improper position may escape being counted, representing an overfeed to the package. Though this type of error obviously will present no problem with customer relations, on the other hand, with parts of high unit cost, such as socket head cap screws, over a period of time the error will represent a considerable loss to the manufacturer or packager. Also improperly positioned pieces, after passing a clearing wheel, may cause a parts jam at a subsequent operation, and therefor require continual attendance upon the machines involved.

By the present invention there is provided a novel arrangement and mutual disposition of the feed track and rejection wheel obviating the above discussed difficulties. The present invention proposes that below the wheel,

2

that is, downstream of or on the discharge side of the wheel, a light restraining means be provided for decelerating parts moving on the track, whereby the parts just before the wheel and passing thereunder are caused to close up and come into contact with each other. The degree of the restraint is such that when a certain length of the group of parts in contact and feeding toward the wheel is initially established, the parts thereafter readily pass the restraining means, as it were under a "static head," as further parts are continually fed to the closed-up group.

With the parts closed up in this fashion in the region of the rejecting wheel, those properly suspended by their heads with shanks within the track structure readily pass as usual beneath the wheel. A part sliding on the cylindrical surface of the head is deflected by contact with the parts between which it is sandwiched either to drop the shank between the track members and thus come into proper position, or to have the shank or some other part of the piece cock up in such fashion that the piece either falls sideways off the usually beveled track or is brought into the path of the toothed parts of the rotating wheel. In any event improperly positioned pieces are thus rejected by the described arrangement, and only properly oriented pieces move toward the discharge point. In the usual environment, the parts are rejected into a bin or auxiliary hopper returning the pieces to the mechanism loading the track.

In the specific form of the invention hereinafter disclosed the deceleration or restraint upon movement of the pieces in the region of rejection wheel is provided in the case of an inclined feed track by a "wavy" track portion, that is, by changing the slope of the track either to a more shallow slope or a short horizontal track portion beyond which the track is again more sharply inclined to accelerate the parts. It is to be understood however that other means may be utilized for thus restraining the pieces beneath or slightly beyond the rejection wheel to cause the pieces to close up into immediate contact as previously described, with the restraining means however permitting ready flow of the parts by virtue of an accumulation of others following along the higher reach of the track before the wheel.

The general object of the present invention is then the improvement of a rejection wheel and feed track combination to minimize feeding of improperly positioned parts, particularly parts such as socket head cap screws.

Another object of the present invention is the provision, in a feed track and rejection wheel combination for feeding socket head cap screws and the like, of means to ensure feeding only of properly positioned pieces, yet which is adapted to feed short shank screws equally well with longer shank screws.

Another object is the provision of a simple expedient ensuring against feeding of improperly positioned parts past the rejection wheel in the feed track system. Other objects and advantages will appear from the following description and the drawings of one embodiment of the invention and the drawings thereof, wherein:

FIG. 1 is a fragmentary view, showing in side elevation, the rejection wheel and the adjacent portions of the feed track embodying one form of the present invention;

FIG. 2 is a fragmentary sectional view taken substantially as indicated by the line 2—2 in FIG. 1 and showing a socket head cap screw properly suspended in the track; and

FIG. 3 is a view corresponding generally to FIG. 2 but showing the disposition of a cap screw relative to the track and rejection wheel groove and notches, when the cap screw is riding on the cylindrical head surface, and so disposed to escape the action of the rejection wheel.

In the drawings there is shown in fragmentary form

(see FIG. 1) a rotating rejection wheel W supported by drive shaft 10 above and for rotation in the vertical center plane of a feed track, i.e., the plane of movement of parts adjacent the wheel. The track comprises an upper reach or upper track portion 11 sloping down toward the wheel and a lower reach 12 more sharply inclined, with a "wavy" section therebetween. Means (not shown) for rotating the wheel, for bringing the pieces to be fed, such as the socket head cap screws P, onto the upper reach of the track, for causing the pieces to move along the track as by vibrating the upper reach of the track in its plane, and for mounting the several structures and also their general mutual disposition, as such are old and may be those as described in detail in the prior Batchelder Patent 2,825,489 issued on March 4, 1958.

The upper track structure 11 comprises the spaced track rail members 14, 14, on the top surfaces or edges of which the parts or cap screws P are supported under their heads with the shanks dependent in a slot formed therebetween; the rail members at least over a portion of the track above the wheel being outwardly downwardly beveled away from the head supporting edges so that improperly positioned pieces may the more readily fall away from the track before reaching the region of the rejection wheel. The rails are shown as having bolted to the outer faces side skirts 16 with overlapping inward bottom flanges. These skirts form no part of the present invention, but are merely means to divert debris dropping from the track away from antecedent portions of the feeding mechanism. The lower reach likewise is formed of a pair of spaced rails for similar support of the parts.

It is to be noted, however, that at the lower end of the upper reach 11, in the region beneath the wheel, the aforementioned "wavy" part of the track terminates the main straight downward slope of the upper reach, so that the part supporting surface rather abruptly curves and flattens out at 17 into a short generally horizontal section or length in the region 18 immediately beneath the wheel, which then through an upwardly convex region 19 round down again to an increased slope merging into the direction of the top or head supporting surface of the usually stationary lower reach 12, the lower reach here being shown with a slope greater than that of the upper reaches. The lower reach 12 thus is offset from the end of the straight slope portion of the upper reach 11 by and through a track hump or wave, which in initially flattening out from the track upper reach accordingly slows down parts in the region 17 to 19 and restrains their motion on the track, whether the pieces are fed simply by gravity and by pressure of pieces above the offset region, say with an upper reach slope on the order of 35°, or by longitudinal or other vibration of an upper reach of smaller slope, e.g., of 20°.

The form of the rejection wheel W is generally that as known to the prior art, having a circumferential groove 20 with a cross sectional shape similar to that of the axial section of a head of a part to be fed to provide a working clearance for the heads of parts passing thereunder in proper position; and it also has a circumferentially spaced set of notches deeper than the groove, resulting in rejection teeth 21, each with a rather sharply sloped front or impact face 21a and preferably a more gradually sloped rear face 21b. The wheel is rotated rapidly in such direction that its bottom track adjacent portion is moving counter to the direction of part feed.

FIG. 2 shows the general shape of the track groove 20 in relation to the head of a part to be fed such as the socket head cap screw P and relative to the track rails 14 with the part properly suspended thereon by its head with shank dependent between the rails 14.

FIG. 3, generally similar to FIG. 2, illustrates a condition which may occur particularly in the case of

socket head cap screws with relatively short shanks, where a high center of gravity allows the cap screw to be supported on the track edges on the cylindrical surface of the head. In such case because of the breadth of the groove carried in practically to its full depth as dictated by the shape of the cap screw head, with a normal track passing under the wheel with no decrease in slope, the piece may itself pass under the wheel through the groove as is obvious in FIG. 3 and thus escape rejection despite its improper position.

However in consequence of restraint and deceleration by the track formation in the region 17, 18, 19, as above described in the region beneath the track rejection wheel, parts initially coming down the upper reach of the track slow up when they reach the wavy region, on starting up feeding operations may even come to a stop, and following pieces then close up against preceding pieces in a closed-up array extending upstream beyond the wheel as indicated in FIG. 1. Further pieces being continually added to the closed up array on the upper reach of the track 11 then provide pressure causing the foremost parts to pass on over the hump or the region of zero slope. With steady full feed although the parts may thus close up, fast discharge is nonetheless attained below or downstream of the rejection wheel over the lower reach 12.

With the parts generally closed up in the region represented by FIG. 1, any piece coming down the track in a position or disposition, such as that represented by FIG. 3, upon coming in contact with a preceding piece and particularly upon contact therewith by a following piece, is cocked off the track sideways to roll off the bevel; or has its shank deflected downwardly between the track rails 14 into proper suspended disposition of the whole piece; or has the shank or other portion cocked upwardly into the path of teeth of the rotating clearing wheel to be thrown out of the track. Thus in the combination and arrangement here shown it is ensured that only properly positioned pieces will pass through the rejection wheel region to the lower feed track.

The above disclosed form and shape of the track in the region of the rejection wheel generally offers means for restraining parts in the region indicated which is much simpler than other expedients such as light flat leaf springs on opposite sides of the track, magnets or other means for applying such restraining force.

I claim:

1. In a device of the type feeding headed parts in soldiered array in a vertical plane along a feed track, improved means for ensuring against discharge of improperly positioned pieces comprising: a said feed track adapted to support parts being fed thereon suspended by their heads with shanks dependent in the feed track structure, a toothed and circumferentially grooved clearing wheel rotatable in the plane of the feed track with an edge of the wheel proximate to the track and adapted to permit properly suspended parts to pass thereunder on the track, and means associated with the track adapted to apply locally in the region of the wheel a force lightly restraining parts against force inducing movement of parts under the wheel, thereby to cause succeeding parts to form a closed-up array of parts moving toward and under the wheel.

2. In a device of the type continuously feeding headed parts in soldiered array in a vertical plane along a feed track, improved means for ensuring against discharge of improperly positioned pieces comprising: a said feed track adapted to support of headed parts being fed thereon suspended by their heads with shanks dependent in the feed track structure, a toothed and circumferentially grooved rejection wheel rotating in the plane of the feed track with an edge of the wheel proximate to the track adapted to permit properly suspended parts to pass thereunder on the track, and means associated with the track and acting locally on parts in the track on the discharge side of the

wheel to decelerate the same, thereby to cause succeeding parts to form a closed-up array of parts moving toward and under the wheel.

3. The improved means as described in claim 2, wherein: said feed track comprises an upper reach inclined downwardly toward said wheel and, offset from the upper reach a more sharply inclined lower reach; and a track section leading from the upper reach to lower reach having beneath the wheel a portion of lower slope providing said means for decelerating the parts.

4. In a track type feeder structure adapted for feeding headed parts and particularly socket head cap screws and the like with heads suspended on top surfaces of and shank portions dependent within a slot formation of the track structure: a downwardly inclined upper track reach, an inclined lower track reach, a track portion leading from the lower end of the upper reach to the upper end of the lower reach and including a short region of substantially zero slope, and a toothed rotatable rejection wheel having a circumferential groove of cross section similar to and providing operating clearance relative to the heads of pieces suspended in the track structure, said wheel being disposed for rotation above and in the plane

of said track with the wheel edge proximate to in the region of substantially zero slope of said track portion.

5. In a track type feeder structure adapted for feeding headed parts and particularly socket head cap screws and the like with heads suspended on top surfaces of and shank portions dependent within a slot formation of the track structure; a downwardly inclined upper track reach, more sharply inclined lower track reach, a track portion leading from the lower end of the upper reach to the upper end of the lower reach and including a short region of markedly lower sloped than that of the upper reach, and a toothed clearing wheel having a circumferential groove of cross section similar to and providing operating clearance relative to the heads of pieces suspended in the track structure; said wheel being disposed for rotation above said track with the wheel edge proximate to the said region of markedly lower slope.
